BUTTON FEEDING MECHANISM

James Forca, Brooklyn, N. Y., assignor of forty
per cent to Louis Schain, Brooklyn, N. Y.

Application June 28, 1945, Serial No. 602,082

9 Claims. (Cl. 112—113)

1

This invention relates to sewing machines and more particularly to sewing machines constructed to attach buttons.

An object of the invention is to provide a machine which will automatically feed buttons into the clamp of the presser foot. A further object is to provide a machine which will not only feed in the buttons but will register them and align them correctly so that the holes in the buttons will be placed in proper alignment with the needle of the machine. A still further object is to provide means on the machine which will feed the buttons in with the correct side up. There have been machines for feeding buttons into the clamp of the presser foot but most of these machines require that the buttons be fed into the feeding mechanism right side up. An object of this invention is to provide a device which will automatically reject buttons coming from a hopper if the buttons are not right side up. When buttons are placed in the clamp of the presser foot of a button sewing machine, the holes must be placed in a predetermined place in relation to the needle. When this is done manually it is a tedious operation requiring considerable time and accuracy. On my improved machine this will be done automatically. Other objects and advantages become apparent from an examination of the accompanying drawings and from the following description. In the accompanying drawings:

Fig. 1 is a top plan view of my invention applied to a conventional button sewing machine.

Fig. 2 is a side elevation thereof.

Fig. 3 is a detailed elevation of the button sorting mechanism.

Figs. 4 and 5 are detailed views showing the operation of the test rod.

Fig. 6 is a detailed elevation of a portion of the mechanism shown in Fig. 3.

Fig. 7 is a further detail taken on the line 7—7 of Fig. 8.

Fig. 8 is a detailed plan view showing a trap-door.

Fig. 9 is a plan view of the button selecting mechanism.

Fig. 10 is a detailed view of a portion thereof.

Fig. 11 is a plan view of the button feeding mechanism.

Fig. 12 is a rear elevation of the button feeding mechanism.

Fig. 13 is a detailed view thereof.

Fig. 14 is a sectional view of said button feeding mechanism.

2

Fig. 15 is an elevation of a portion of said mechanism.

Fig. 16 is a plan view of the mechanism shown in Fig. 15.

5 Figs. 17 and 18 are other detailed views.

Fig. 19 is a detailed view of the means for setting the mechanism in motion.

Fig. 20 is a detailed view of the button positioning mechanism.

10 Fig. 21 is another view thereof.

Fig. 22 is a cross-sectional view of the button feeding mechanism.

Fig. 23 is a perspective view of a cam plate.

15 Fig. 24 is a perspective view of a plate bearing register pins.

Fig. 25 is a view of a device for setting the button feeding mechanism in motion.

Referring more particularly to the drawings, my invention consists of two main elements.

20 The first of these consists of the mechanism which checks buttons fed from a hopper and rejects those through a trap-door which fall into the slide in an upside down position. The buttons then continue on the slide and are fed into

25 the mechanism forming the second phase of the invention, which feeds the buttons into the jaws of the clamp on the presser foot and registers the alignment of the thread holes in the button so that the descending needle will pass through the holes and not engage the surface of the button.

30 My device is adapted to be fastened to the conventional machine 30 which is provided with the usual presser foot 31 with clamping jaws 32. The device is preferably mounted on the shaft 34 so that it may be swung out of engagement if desired.

35 Any suitable means may be used to power the device and the power may be taken either from the sewing machine itself or supplied by a separate motor.

40 Referring now to Figs. 1 to 10, inclusive, and more particularly to Figs. 3 to 10, inclusive, I provide a shaft 35 which is shown in Fig. 3 and is powered by means of a belt 36 on the pulley wheel 37. Mounted on the shaft 35 are a series of cam members 38, 39 and 40. A slide 41 leads from a hopper (it is not shown) and buttons move down this slide to the selecting mechanism. Mounted on the upright 42 is a carriage 43. The carriage 43 is mounted by two depending rods 44 and 45 on at least one of which is a spring 46 which tends to push the carriage 43 upwardly. A pin 47 limits the upward movement of the carriage 43. On the cam member

38 is an arm or finger 48 and a depending adjustable cam 49. It can be seen that the cam 49 may be adjusted by loosening and tightening the screw 50. As the shaft 35 rotates the cam 49 engages a lateral extension 51 on the carriage 43, thus depressing the entire carriage a predetermined distance against the spring 46. The distance that the carriage 43 would be depressed depends upon the setting of the cam 49.

Mounted on the carriage 43 is a lever 52 pivoted at 53. A spring 54 tends to limit the movement of the lever. The lever 52 engages a link 55 which in turn engages a forked arm 56 by means of a pin 57.

The chute, or slide, 41 passes over a floor plate 60 in which is mounted a trap door 61. On the bottom of the floor plate 60 is connected a mechanism 62 with a latch 63 therein. The latch 63 tends to normally keep the trap-door closed. The trap-door has a raised surface 64 conforming with an opening 65 in the floor plate. The arm 56 connects with another arm 66 which engages the latch member 63. As shown in Fig. 7 the spring 67 normally forces the latch into the locked position. The arm 66 has a cam face 68 engaging an opening in the latch, so that when the arm 66 is raised the latch will open. Pivotally mounted on the carriage 43 is a latch member 70 having a cutout portion within which the pin 71 mounted on the arm 56 rides. The end 72 is turned at right angles and is adapted to be engaged by the catch 73 normally pressed into the position shown by dotted lines in Fig. 3 by the spring 74. When the end 72 of the member 70 is engaged by the catch 73, the sliding section of the pin 71 will hold the arm 66 in a lowered position and the cam face 68 out of engagement with the latch 63 so that the trap-door 61 will remain closed.

Mounted on the cam member 38 is the finger 48, and as the shaft rotates this finger 48 will engage the top of the lever 52 at each rotation, thus pressing the arm downwardly and allowing the catch 73 to engage the end 72 of the member 70. Mounted on the lower cam member 49 is an upstanding cam 76 adapted to engage the finger 76 mounted on the shaft 77, which, in turn, operates the lever 78 on the rod 79 so that the rod 79 will engage the underside of the trap-door 61 to close the same if it is open. A spring 83 maintains the rod 79 in engagement with the bottom of the trap-door. Also mounted on the carriage 43 is the feeler rod 85, which can be adjusted so as to limit the travel in one direction by means of the ring 86 and which carries an adjustable trip 87. Between the carriage and the trip 87 is a spring 88 pressing the rod downwardly. When in its normal position, as shown in Fig. 3, the tip rests just below the end 72 of the latch 73.

The buttons come down the chute 41 and are fed under the feeler rod 85. As the cam 49 depresses the carriage 43, the feeler rod 85 will be carried downwardly a predetermined distance. If the button is right side up the feeler rod 85 will go into the hollow portion thereof and nothing will happen. In the event the button is wrong side up, the end of the feeler rod will connect with the button, thus forcing the rod upwardly against the spring 88, tripping the latch 73, allowing the spring 89 to pull the arm 56 and with it the arm 66 upwardly, which results in the cam face 68 pulling the latch 63 into the open position, at which time the spring 83 pulls the trap-door open, allowing the button to fall out into a suitable receptacle. As the shaft rotates the finger 48 will depress the arm 52 re-latching

the member 70. At the same time the cam 75 will close the trap-door 61. Mounted above the chute 41 is an upright 90 in which is pivoted a shaft 91. Mounted on the shaft 91 is an arm 92 and a second arm 93. A finger 94 is positioned in the upright 90 and carries the collar 97. The collar 97 is positioned by means of the springs 98 and 99 and the collar 97 is engaged by the arm 93. Spring 95 cooperates to tension the position of the finger 94. The cam member 39 has a cut out portion 96 and as the shaft rotates it engages the arm 92, thus depressing the finger to prevent the buttons from moving down the chute except during the period when the portion 96 passes over the arm 92. This results in the finger allowing one button to come down the chute at a time. Just below the finger 94 are pivoted a pair of arms 100 and 101 with their outer ends tensioned towards each other by the spring 102. A second pair of arms 103 and 104 are pivoted and have their ends slidably engaging the arms 100 and 101, as shown in Fig. 10. The pins 105 extend upwardly over the housing 106 where they engage a third pair of arms 107 and 108. A slidable cam member 109 is provided and is engaged by the arm 110, which, in turn, is operated by arm 111. Mounted adjacent to pulley wheel 37 is a concave cam member 112 which on each revolution engages the end of the arm 111, thus operating the sliding cam member and causing the arms 103 and 104 to move away from each other temporarily, thus releasing the button held by said arms and allowing another button to move into its place.

It will be seen that as each button is moved into place the feeler rod 85 moves downwardly, as shown in Figs. 4 and 5. If, as shown in Fig. 5, the button is upside down, the discard mechanism will be put into action. If, on the other hand, the button is as shown in Fig. 4, it will be allowed to pass on down the chute 41 into the next phase of the operation.

The chute 41 continues into the button feeding mechanism shown in Fig. 11, etc. This phase of the invention involves two separate mechanical movements, one in which the rack bar 171 picks up the button and moves it under the registering mechanism 126, and the second where the button is turned to register with pins so that it will be in proper position with relation to the needle, then, where the rack moves the button into the jaws 32 of the foot 31. Obviously, this action must be intermittent depending upon when the operator desires a new button to be placed under the needle. I, therefore, provide a clutch mechanism which, in neutral, does not affect either the rack or the turning mechanism and which when moved in one direction will operate only the rack while in the other direction will operate the centering mechanism. This clutch mechanism is operated by a grooved cam.

Referring to the drawings, power may be supplied from the same source as operates the rest of the mechanism. It may be transmitted by means of the shaft 121 through the worm 123 and the gear 129 to the shaft 130 by means of the pinion 131 to the gear 132 closely mounted on the shaft 133. A grooved cam 134 is keyed to the shaft 133 for rotation therewith, and a cam wheel 135 is likewise keyed to the shaft 133. Means, which will hereafter be described, are provided to operatively connect and disconnect, by means of a dog, the gear 132 to the cam wheel 135 so that the shaft will be rotated with the gear 132. Mounted on the shaft 136 is a sliding block 137 resiliently tensioned in one direction by the spring

138. The sliding block 137 carries the finger 139 which engages the groove 140 in the grooved cam 134. It also has an extension 141 which engages the groove 142 in the clutch member 143. The clutch member 143 is provided on one side with a lug 144 and with a similar lug 145 on the other side. It will be noted that the clutch is keyed to the shaft 139 by means of the key 146 so that it will rotate with the shaft. When the cam wheel 135 is engaged by the pin 150 on the dog 151, the grooved cam 134 will rotate and the block 137 will move first to one side and then to the other. When it moves to the left the lug 145 will engage the pin 155 on the gear 156, thus causing it to rotate and to cause with it the rotation of the gear 157 which carries the crank arm 158. The crank arm 158 engages the link 159 pivoted at 160 through an extension 161 to allow for clearance. The link 159 has an elbow 162 engaging the arm 163, which is pivoted at 164 to the gear 165. As the gear 157 is rotated by the gear 156 the action of the crank arm and the link causes the gear 165 to move first clockwise and then counter-clockwise, thus transmitting the motion to the pinion 136 on the shaft 167.

Mounted on the other end of the shaft 167 is a pinion 168 which engages the rack 170 on the sliding bar 171 recessed in the base 172. The bar 171 is provided with a button engaging portion 173 and has mounted thereunder a plate 175 carrying a pair of pins 176. Mounted on the pins is a cam plate 177 having a pair of apertures 178 adapted to accommodate the pins 176 and a cam surface 179 is adapted to engage a recess 180 at the bottom of the bar 171. When the bar is in the retracted position the cam 179 will slide into the recess 180, so that the pins 176 will extend through the apertures 182 in the bar 171 to position the button in proper alignment. When the bar 171 is in the extended position the cam 179 will ride out of the recess 180 to depress the pins 176 so as to leave the button free. It will be appreciated that the plate 175 is secured to the bar 171 while the cam plate 177 rides on the plate to the extent that the pins 176 move in the slots 178 so that when the bar 171 is brought back the cam plate stays in the same position and the cam 179 disengages the recess 180. When the bar 171 is moved back the cam again engages the recess 180, and the cam plate slides on the pins 176.

It will be readily understood that with the pinion 168 engaging the rack 170, the bar 171 will be extended and retarded whenever the pin 155 and the gear 156 are engaged by the lug 145. As the bar is extended it will feed the button into the jaws 32 of the foot 31. Mounted adjacent the slide 41 is an upright 185 through which extends a shaft 186 on which is mounted an arm 187 carrying the finger 188. The action of this arm is controlled by arm 184 engaging the shaft 186 and contacted by the sliding lever 189, which, in turn is operated by the pivoted arm 190, having an end 191, which is engaged by the projection 192 on the bar 171. When the bar is returned to the retracted position the projection 192 will cause, through the pivoted arm 190, the slide lever 189 to push the arm 187, pressing the finger against the buttons in the chute to prevent further feeding. Mounted on the bottom of the arm 187 is a stop 193 which, by reason of a spring 194, holds the buttons in place until the action of the sliding lever 189 causes the finger 188 to grasp the next button, thus it will be seen that only one button is released at a time.

As one button is fed into the jaws of the clamp

another is deposited on the bar 171 under the positioning mechanism 126 and the bar 171 brought into retracted position. At this point the cam sleeve 134 reaches a point where the lug 145 disengages the pin 155 and the clutch moves to the right where the pin 200 on the gear 201 is engaged. This causes rotation of the gear 202 on the shaft 203. On the other end of the shaft 203 is a bevelled gear 204 which engages another bevelled gear 205 on a shaft 206. The shaft 206 is provided with a gear 207 engaging the gear 208 on the vertical shaft 209. The shaft 209 is mounted in the fixture 210 which carries a female cam section 211. A corresponding member with a cam 212 is mounted on the shaft 209 and a spring 214 is provided to tension these parts together. The lower part of the support 215 positions said spring. On the lower end of the shaft 209 is a button rotating member 216 having a soft under-surface 217. The under-surface 217 is designed to contact the button and it may be made of sponge rubber or any suitable material. As we have previously seen, the action of the bar 171 in an extended position places the button between the jaws of the clamp 32 and at the same time places another button underneath the button rotating member 216. This is done when the cams 211 and 212 are in complete register and the button turning mechanism slightly raised.

As the pin 200 is engaged by the lug 144 and the shaft 203 set in motion, the shaft 209 is caused to rotate. At the same time the bar 171 is retracted to a position where the cam 179 moves into the recess 180, so that the pins 176 move upwardly to engage diagonal holes in the button as it is rotated upon the pins. The shaft 209 completes its rotation as the grooved cam 134 rotates to a point where the pin 139 moves the clutch into a neutral position and the button immediately under the rotating and aligning device moves back into the raised position ready for another operation. The spring members 218 may be provided to position the button more securely. In order that the shaft 203 may remain dormant when the clutch is in the neutral position, a notched wheel 320 is provided on the outer end thereof adapted to be engaged by the spring 321 and a similar notched wheel 322 is fastened on the end of the shaft 133 and engaged by the spring 334.

A more detailed view of the action of the dog 151 carrying the pin 150 is shown in Figures 15 to 18, inclusive. We see that the gear 132 is mounted adjacent to the cam wheel 135. The end 220 of the pin 150 extends through a slot 221 in the gear 132 and the dog is pivoted at 222 so that the pin may slide in the slot 221. It will be seen that when the pin is in position at the inner end of the slot, the pin 150 will engage the cam wheel 135 to place the shaft 133 in motion. When the pin is moved to the other end of the slot, or the outer end of the slot 221, the pin will clear the surface of the cam wheel 135. Attached to the dog 151 is a link 225 which, in turn, is attached to an arm 226 pivoted at 227 to the lever 224. The lever 224 is pivoted at 230 to the gear 132. It will be seen that pressure on the end 231 of the lever 224 will be transmitted through the arm 226 and the link 225 to throw the dog so that the pin 150 will move to the outer position of the slot 221.

This action is controlled by the mechanism shown in Fig. 19, which consists of the shaft 250 upon which is mounted the trip block 251, the lever 252, the finger 253 and the trip 254. The

trip block 251 has an upwardly extending finger 255 and a downwardly extending finger 256. The upwardly extending finger 255 is adapted to be put into action by means of a push rod 257 which mounts a block 258 adapted to engage the finger 255 to push it forward in a clockwise direction on the shaft 250. This causes the catch 259 to move under the cam block 260 to tilt the shaft 250 in a clockwise direction. A spring (not shown) normally pushes the catch block forward. As the gear 132 rotates, the finger 262 on the trip 254 engages the pin 150, forcing it inwardly in the slot 221 to a position where it engages the cam wheel 135 to rotate the shaft 133 through the cam wheel 135. The start of this action is indicated in Fig. 18. As the gear 132 rotates, the finger 263 engages the end 231 of the lever 224 throwing the dog 151 and moving the pin 150 to the outer edge of the groove 221 and out of engagement with the cam wheel. As the shaft 133 rotates, the cam 265 on the cam sleeve 134 engages the end of the lever 252, thus exerting pressure on the pall 266 causing it to assert pressure against pin 267 withdrawing the catch block 259 and allowing the shaft 250 to turn in a counter-clockwise position motivated by a spring attached to the end of the block 263, not shown in Fig. 19 but shown in Fig. 11 as 269, thus disengaging the mechanism.

In Fig. 25 is shown a method for automatically setting the machinery in motion. There the presser foot 32 is engaged by an adjustable screw pin 275 so that when the presser foot is raised upon the finishing of the sewing, pressure will be exerted through the pin 275 against the right-angled arm 276 to rotate the shaft 277 and then exert through the arm 278, tilting pressure against the finger 256 on the block 251. The shaft 277 will, of course, pass through the plate 279.

It will be appreciated that the foregoing description is for the purpose of describing preferred form of my invention with which buttons may be fed continuously from a hopper A of any suitable tube through the rejecting mechanism which has a suitable container B for the rejects through the chute 41 and into the clamp 32 in correct alignment for sewing.

It will also be appreciated that many modifications and variations in the arrangement and sequence of operation and general assembly of my invention can be made without departing from the essential principles disclosed.

I claim:

1. In a device of the character described a plurality of register pins, means for rotating a button until the holes in said button register with said pins, means for moving said button into the holding clamps of a sewing machine foot, and means for selectively operating the first two mentioned means, said last mentioned means including a clutch, a grooved cam adapted to move said clutch alternately into engagement with operating mechanism for said first and second means.

2. In a device of the character described means for feeding buttons into the jaws of a sewing machine foot, means for positioning said buttons to register them with the needle of the sewing machine, means for operating said first mentioned means including a clutch, a grooved cam engaging said clutch, to move it in and out of engagement with the respective operating means, means for selectively actuating said cam, said means including a shaft, a cam wheel on said

shaft, a gear rotating freely on said shaft, and means on said gear to engage said cam wheel to rotate said shaft.

3. In a device of the character described means for feeding buttons into the jaws of a sewing machine foot, means for positioning said buttons to register them with the needle of the sewing machine, means for operating said first mentioned means including a clutch, a grooved cam engaging said clutch, to move it in and out of engagement with the respective operating means, means for selectively actuating said cam, said means including a shaft, a cam wheel on said shaft, a gear rotating freely on said shaft, and means on said gear to engage said cam wheel to rotate said shaft, and additional means for disengaging said cam wheel after one rotation thereof.

4. In a device of the character described a plurality of register pins, means for rotating a button until the holes in said button register with said pins, means for moving said button into the holding clamp of a sewing machine foot and means for selectively operating the first two mentioned means, said last mentioned means including a clutch, a grooved cam adapted to move said clutch alternately into engagement with the operating mechanism of said first and second means, said grooved cam being mounted on a shaft, a rotating gear freely mounted on said shaft, a cam wheel adjacent said gear on said shaft, means on said gear to engage said cam wheel to rotate said shaft and means to automatically disengage said cam wheel from said gear after one complete operation.

5. In a button sewing machine having a button holding clamp, means for selectively feeding buttons to said button holding clamp, said means including a chute, a reciprocating bar under said chute, means for selectively feeding buttons from said chute to said bar, means for moving said bar and means for rotating said buttons to a predetermined position.

6. In a button sewing machine having a button holding clamp means for selectively feeding buttons to said button holding clamp, said means including a chute, a reciprocating bar under said chute, means for selectively feeding buttons from said chute to said bar, means for moving said bar and means for rotating said buttons to a predetermined position, said last mentioned means comprising a shaft, a button rotating member on said shaft and means for moving said shaft downwardly to contact said button and rotate the same.

7. In a button feeding mechanism a chute, means for moving buttons intermittently along said chute, a door in said chute, a finger positioned above said door, means for causing said finger to move downwardly a predetermined distance as buttons are moved along said chute and over said door, a latch on said door, means co-operating with said finger to open said latch if the travel of said finger is interrupted by a button and means for closing said door before the next button is moved into place.

8. In a button feeding mechanism a chute, means for moving buttons intermittently along said chute, a door in said chute, a spring catch on said door, a finger positioned above said door, means causing said finger to move downwardly a predetermined distance as buttons are moved along said chute under said finger, means co-operating with said finger to release said latch

if said finger contacts a button and means for closing said door, said means consisting of a rotating cam.

9. In a button sewing machine means for feeding buttons, said means including a chute, a door in said chute, a carriage, a finger mounted on said carriage, latch means for opening said door operatively connected to said finger, means for selectively feeding buttons down said chute, cam means for causing reciprocal movement of said carriage, cam means for resetting said latch means, cam means for operating said button feeding mechanism, and cam means for closing said door.
